FLOOR OILER AND WAXER

Edgar F. Hawley, Pueblo, Colo.

Application March 25, 1933. Serial No. 662,775

5 Claims. (Cl. 91—39)

This invention relates to devices for oiling and waxing floors and particularly to a device of this character in which there is provided a tank for containing oil or liquid wax movable over the floor and provided with brushes for rubbing in the oil or wax and polishing the floor.

The general object of the invention is to provide improved means whereby the brushes may be mounted upon the tank and whereby they may be adjusted so as to be used until practically all the bristles have worn away.

A further object is to provide a structure of this character comprising an oil tank mounted upon wheels and carrying brushes, providing a spraying device for spraying the oil on to the floor in advance of or through one or more of the brushes and provide a manually operable pump whereby the oil may be sprayed from time to time on to the floor and in this connection to provide means whereby the handle of the oiler and waxes may be used to operate the pump.

Other objects will appear in the course of the following description.

My invention is illustrated in the accompanying drawing, wherein:

Figure 1 is a side elevation of my oiler and waxes;

Figure 2 is a top plan view thereof;

Figure 3 is a longitudinal section showing in dotted lines the handle broken and the plunger raised.

Referring to this drawing, 10 designates a tank generally of any suitable material or construction which may have any desired form in plan. This tank is provided with the floor or bottom 11 supported on wheels 12 and the tank is provided with an inlet opening 13 through which the tank may be filled and which may also be used as a vent for permitting the inlet of air when the liquid is allowed to flow from the tank.

Mounted upon the exterior of the tank at the front and rear thereof are the guide brackets 14 extending through which are the bolts or spindles 15 which carry the brushes 16, the heads of which are designated 17. These brushes extend transversely across the tank and one brush is located at the front of the tank and another at the rear of the tank. A coiled spring 18 surrounds each spindle or bolt 15 and bears against the lowermost bracket and against the head of the brush and thus the brushes are urged downward. This downward movement of the brushes, however, is limited by nuts 19 carried upon the upper ends of the spindles 15 or bolts and bearing against the uppermost brackets 14.

By tightening these nuts or turning them downward, against the bracket 14, the spindles and, therefore, the brushes are raised, compressing the springs 18. By turning the nuts off to any desired degree, the brushes will be forced downward by the springs 18. Thus as each brush wears, the corresponding nut 19 may be turned off to any desired degree to allow the brushes to move downward and thus the brushes may be used until practically all of the bristles have worn off.

Within the tank 10 there is disposed the false bottom 20 dividing the tank into two portions. The upper portion 21 constitutes an oil reservoir or liquid wax reservoir while the lower portion 70 is empty. Extending downward through the top of the tank and through this false bottom 20 and to the bottom 11 of the tank is a cylinder 22 provided with an air inlet opening 23 adjacent its top and below the top of the tank 10 and 75 just above the false bottom 20 being provided with the inlet openings 24. Operating within the cylinder is a piston 25 having a piston rod 26 which extends out through the top of the cylinder and is provided at its upper end with an eye 27. 80

Mounted upon the top of the tank are the two spaced brackets 28 which are each approximately triangular in form and attached to the top of the tank in any suitable manner, these brackets having extensions 29 which extend upward 85 and rearward from the tank. The upper handle section 30 is pivoted at 31^a between these brackets 28 as shown in Figure 2.

Coacting with the upper handle section 30 is a lower handle section 31, it being understood 90 that these two handle sections together constitute the handle and these two sections are hinged to each other by a hinge 32 whose pintle is disposed in alinement with the joint 33 between the two sections. Extending from the handle section 31 is an elongated downwardly and forwardly extending shank 34 whose end is curved as at 35, the extremity of this curved portion passing through the eye 27. Disposed above and below the shank 34 are the fulcrum pins 36 and 37 which extend from one bracket extension 29 to the other. These pins 36 and 37 each constitute a fulcrum for the shank 34 which, with the handle section 31, constitutes a lever whereby the plunger may be raised or lowered as will be later explained. A coiled contractile spring 38 is attached to the handle section 30 and to the top of the tank and acts to draw the handle section 30 downward.

Leading from the lower end of the cylinder 22

- is a discharge pipe 39 which extends to the front wall of the casing or tank 10, then extends upward to the top of the tank and then extends directly downward as at 40 and terminates in a transversely extending spray head 41 having a plurality of perforations discharging downward through a slot 42 formed in the head 17 of the front brush. This slot 42 extends entirely through the brush head to the floor so that the spray from the sprayer 41 is discharged downward through this slot and through the bristles of the front brush on to the floor.

The operation of this mechanism is as follows:—Of course the machine is designed to be pushed and pulled over the floor to be polished and the oil or liquid wax is designed to be forced by the pump piston out through the sprayer.

- Assuming that the reservoir 21 is more or less filled with oil or liquid wax and it be desired to force oil or wax on to the floor, then the handle section 30 is raised, turning upon its fulcrum 31^a. This, through the hinge 32, causes the depression of the handle section 31 and the depression of the rear end of the lever constituted by the shank 34 acting against the fulcrum pin 36. This will act to lift the plunger 25 above the openings 24 so that oil will flow into the space between the plunger 25 and the lower end of the cylinder 22. Upon a depression of the handle section 30, the parts will be brought back to the position shown in Figure 3, causing the lever constituted by the shank 34 to bear against the fulcrum 37 and thus depressing the forward end of the shank and depressing the plunger, thus positively forcing the oil in the cylinder out through the pipe 39 and on to the floor. With this mechanism, whenever it is desired to force oil or wax out in advance of the polisher, the handle section 30 is oscillated which will have this effect. The spring 38 keeps the jointed handle rigid while operating the machine back and forth across the floor. With this construction, there is no necessity of the operator stooping in order to operate the pump and it avoids the necessity of the operator placing his foot on top of the oiler in order to balance the same while pumping oil.

A mechanism constructed in accordance with my invention distributes liquid when and where desired at the will of the operator. In operation it has been found to save oil, prevent the smearing up of floor boards, casings or woodwork and is easy to operate. The handle serves a double purpose of propelling the machine back and forth and actuating the plunger. A normally operating position is obtained except when the plunger is being raised or lowered. The ejection of the liquid is entirely under the control of the operator.

While I have illustrated a particular construction, I do not wish to be limited to this as obviously many minor changes can be made therein without departing from the spirit of the invention as defined in the appended claims.

What is claimed is:

1. An oiler or waxter of the character described including a tank for containing liquid, brushes carried upon the under side of the tank, a pump having its cylinder operatively connected to the interior of the tank and having a discharge pipe provided with a sprayer, a plunger operating within the pump cylinder, means for operating the plunger including a handle whereby the oiler may be pushed and pulled, said handle being pivotally supported upon the top of the tank and having an operative connection to the plung-

er, the movement of the handle in one direction away from its normal position upon its pivot acting to raise the plunger and permit the passage of liquid from the tank into the space beneath the plunger and in the other direction to normal position acting to depress the plunger and force out the liquid on to the brushes.

2. An oiler or waxter of the character described comprising a tank, wheels supporting the tank, brushes mounted upon the under side of the tank, a cylinder disposed within the tank and having a discharge pipe leading from its lower end, a sprayer connected with the discharge pipe and adapted to discharge liquid on to the floor immediately in advance of the tank, the cylinder having inlet openings to the interior of the tank and disposed above the lower end of the cylinder, a plunger operating within the cylinder and when raised permitting the inlet of liquid into the lower end of the cylinder and when depressed forcing this liquid out through the sprayer, a handle for pushing and pulling the tank, the handle being pivotally mounted upon the upper wall of the tank, and an operative connection between said plunger and said handle whereby when the handle is oscillated, the plunger will be reciprocated.

3. An oiler or waxter of the character described comprising a tank, wheels supporting the tank, brushes mounted upon the under side of the tank, a cylinder disposed within the tank and having a discharge pipe leading from its lower end, a sprayer connected with the discharge pipe and adapted to discharge liquid on to the floor immediately in advance of the tank, the cylinder having inlet openings to the interior of the tank and disposed above the lower end of the cylinder, a plunger operating within the cylinder and when raised permitting the inlet of liquid into the lower end of the cylinder and when depressed forcing this liquid out through the sprayer, brackets mounted upon the upper face of the tank, and a handle mounted upon said brackets, the handle being formed of an upper and a lower section hinged to each other, the upper section of the handle being pivoted to said brackets above the hinge, the lower section of the handle carrying a member extending downward and loosely engaged with the upper end of the plunger rod and upper and lower fulcrum pins attached to said brackets and extending above and below said member whereby as the upper section of the handle is raised, the lower section of the handle at its rear end will be depressed and when the upper section of the handle is lowered to bring the sections in alignment, the plunger will be depressed, and means resisting upward movement of the upper section of the handle.

4. An oiler or waxter of the character described comprising a tank, wheels supporting the tank, brushes mounted upon the under side of the tank, a cylinder disposed within the tank and having a discharge pipe leading from its lower end, a sprayer connected with the discharge pipe and adapted to discharge liquid on to the floor in the path of movement of the brushes, the cylinder having inlet openings to the interior of the tank and disposed above the lower end of the cylinder, a plunger operating within the cylinder and when raised permitting the inlet of liquid into the lower end of the cylinder and when depressed forcing this liquid out through the sprayer, and a handle operatively supported upon the tank, the handle being formed of an upper

and a lower section hinged to each other, the upper section of the handle being operatively pivoted to the tank above said hinge, the lower section of the handle carrying the member extending downward and loosely engaged with the upper end of the plunger rod, and upper and lower fulcrum pins operatively supported upon the tank and extending transversely above and below said member whereby as the upper section 5 of the handle is raised, the lower section of the handle at its rear end will be depressed and when the upper section of the handle is lowered to bring the sections into alignment the plunger will be depressed, and means resisting upward 10 movement of the upper section of the handle.

5. An oiler or waxer of the character described, comprising a tank, wheels supporting the tank, brushes mounted upon the under side of the tank, a cylinder having a discharge pipe leading 15

from its lower end, a sprayer connected with the discharge pipe and adapted to discharge liquid to the floor in the path of movement of said brushes, the cylinder having an inlet opening to the interior of the tank disposed above the lower 20 end of the cylinder, a plunger operating within the cylinder and when raised permitting the inlet of liquid into the lower end of the cylinder and when depressed forcing this liquid out through the sprayer, and a handle operatively pivoted upon the tank and engaging the plunger, the oscillation of the handle in a vertical plane causing the upward movement of the plunger to permit the inlet of liquid thereto and then the 25 downward movement of the plunger to cause the discharge of liquid from the cylinder, and means resisting movement of the handle away from its normal position.
